UNITED STATES PATENT OFFICE.

FREDERICK O. LAWSON, OF TORONTO, ONTARIO, CANADA.

SANITARY SANDAL.

Application filed August 15, 1927. Serial No. 213,090.

The principal objects of the invention are to devise a sandal which will protect the foot of the wearer from being soiled while walking to and from a bath or swimming pool or while in a dressing room, and which will fit snugly to the foot.

A still further object is to devise a form of sandal which will readily adapt itself to fit different sizes of feet.

10 The principal features of the invention consist in forming a sandal with a sole portion of a tough flexible inelastic paper and a vamp portion of an elastic material stitched to said sole portion to form a toe pocket.

15 In the drawings, Figure 1 is a perspective view of my improved sandal as worn upon the foot.

Figure 2 is a plan view of the sandal.

Figure 3 is a cross section through Figure 20 2 on the line 3—3.

The sandal as herein shown is formed with a sole portion 1 of a material impervious to water, such as a close-grained malay, glazed or water-proofed paper of strong texture 25 and a vamp portion 2 formed to conform to the size of the forward portion of the sole and of a material having a marked degree of extensibility permitting expansion to accommodate the forward portion of the foot.

30 The form of sandal may be altered to considerable extent but the principal element is in the use of an elastic material across the upper forward portion which will allow for the proper expansion of the toe pocket 35 when the foot is inserted therein.

The preferred material with which to accomplish the desired result is a strong texture paper for the sole portion and a tough crepe paper for the vamp, the blank being 40 cut with the crinkled corrugations of the paper arranged longitudinally, that is, lengthwise of the sandal and when stitched to the sole portion provides a flexibility which is extremely desirable, in fact it is 45 this feature which makes the sandal of value and practical.

In the manufacture of this class of sandal only one or two sizes are made, but because of the flexibility of the paper stock from which the vamp is made, together with the 50 paper sole, different sizes of feet will fit into the pocket so formed and find comfortable accommodation, the elastic material spreading around the minor shapes of the foot, holding the sandal snugly to the forward portion of the foot without undue pressure.

When the sandal is placed on the foot the edges of the sole portion are drawn upward around both sides of the foot preventing the 60 slushing of water on to the foot surface of the sole portion thereby furnishing further protection to the foot.

The vamp portion being cut to approximately the same size as the toe portion of 65 the sole and stitched around their outer edges forms a sandal of very simple design and an inexpensive article to manufacture which is a very important feature as it enables the management of bath houses to furnish their patrons with this service at a very 70 low cost.

What I claim as my invention is:—

1. A sanitary sandal having a sole portion formed of a flexible fabric, and an upper 75 formed of a unitary piece of extensible fabric placed flat upon the toe end of the sole and secured around the edges.

2. A sanitary sandal having a sole portion formed of a flexible inelastic material, and 80 a vamp portion formed of a unitary piece of material creased longitudinally to render the same laterally extensible, said vamp being of a width corresponding to the width of the sole portion and secured thereto around 85 the edges.

3. A sanitary sandal having a sole portion, and a toe pocket formed of a flat piece of crepe paper of the same shape as the toe end of said sole placed over said sole portion and stitched around the edges.

FREDERICK O. LAWSON.
